UNITED STATES PATENT OFFICE.

LEE W. MELCHER, OF WEST DE PERE, WISCONSIN, ASSIGNOR TO RAILWAY MOTORS CORPORATION, OF DE PERE, WISCONSIN, A CORPORATION OF WISCONSIN.

CONTROLLING MECHANISM FOR CARBURETORS.

Application filed September 17, 1923. Serial No. 663,117.

The invention relates to controlling mechanism for carburetors used with internal combustion engines and its object is to provide improved controlling devices which are adapted to control the carburetor from a remote point, such as the cab of a motor-driven railroad car. Another object of the invention is to provide improved controlling devices which are adapted for very minute 5 adjustments, so that when a plurality of motors are used on a single car, they will be accurately controlled to attain the desired synchronization between the motors. Other objects of the invention will appear from the 10 specification.

The invention consists in the several novel features hereinafter set forth and more particularly defined by claims at the conclusion hereof.

20 In the drawings: Fig. 1 is a plan of a motor provided with the invention. Fig. 2 is a side elevation. Fig. 3 is a horizontal section through the controlling devices.

The invention is exemplified in connection 25 with a motor comprising cylinders 5 in any desired number and around which is formed the usual water jacket 6 for cooling the motor. The motor is provided with the usual water circulating system, such as a 30 pump 9, which receives, through the pipe 10, water from a radiator (not shown) and forces it through a pipe 11 into the water-jacket around the motor cylinder and through a discharge manifold 8 into the 35 radiator. Since these parts may be of the usual construction, it has not been deemed necessary to illustrate them in detail. The pump and its connections serve to circulate water through the water-jacket around the 40 cylinders, and the pump is, as usual, driven by the motor. The latter is mounted on sills 12 which are supported by frame-bars 13 which are suitably secured to the car. Combustible fluid is delivered from a carburetor 15 through the usual pipe and manifold which is connected in the usual manner to deliver the fluid by suction into the motor cylinders, as well understood in the art. The carburetor is provided with the 45 usual throttle-valve 14 for regulating the flow of combustible fluid to the cylinders and correspondingly controlling the speed of the motor. The shaft 16, on which this throttle is mounted, is provided with an 50 arm 17 which is operable by the controlling 55 mechanism hereinafter set forth to regulate and vary the speed of the motor.

The improved controlling mechanism for the carburetor comprises a regulator, which is adapted to be operated responsively to the pressure of the cooling liquid in the water jacket, and an air operated device, controllable at will to operate the throttle valve, subject to the variations in pressure in the cooling liquid. A lever 20, which is centrally pivoted at 22 to the fixed frame-bar 21, and to one end of this lever is connected at 24, a rod 23, which has its other end pivotally connected to the throttle arm 17. The other end is pivoted to a stem 25 which is adapted to be operated by a diaphragm 26 which has its margin confined between the sections of a casing 27. An air pipe 28 is connected to deliver air into one side of the casing to operate the diaphragm in one direction. Pipe 28 is connected to deliver compressed air under control of an operator's valve from a suitable source of air supply, such as an air tank carried by the car and kept automatically filled by the motor, as 60 exemplified in an application filed by me March 5, 1923, Serial No. 622,751. A valve 29 exemplifies one which is located at any controlling station and whereby the operator may cause air under pressure to flow 65 into the diaphragm casing 27 to operate diaphragm 26 and the controller lever 20, the extent of movement of the lever depending upon the pressure of the air admitted to the casing 27. The diaphragm-operated 70 stem 25 is slidably mounted in a plug 37, which is threaded into one section of diaphragm casing 27. This casing is supported by a fixed bar 38 which is clamped between a shoulder of the plug 37 and one 75 end of the casing 27. A spring 30, coiled around a rod 31 which has one of its ends pivoted, as at 32, to lever 20, is interposed between frame-bar 21 and an adjustable nut 33, which is screw-threaded to rod 31. This 80 spring serves to normally hold the lever 20 in position to close the throttle, and by adjusting the nut 33, the resistance of the spring to the movement of the lever may be varied within the desired degrees.

The regulator, which is responsive to the fluctuations of pressure in the water-jacket, comprises a diaphragm 34 which has its margin secured in a casing 35 which is formed of sections. One side of said casing is con-

nnected by a pipe 36 to the water-jacket 6 of the motor, so that the variations in the pressure of the water in the motor will act upon the diaphragm 34. A head 40 is fixed to a stem 41 which is slidably mounted in one side of the casing 35 and said stem is pivoted, as at 42, to the controller lever 20. Head 40 is adapted to be operated in one direction by diaphragm 34, so that the pressure of the fluid in the water jacket and against said diaphragm will constitute a resilient resistance which is automatically varied by the pressure of the cooling liquid to automatically control, in conjunction with the pressure against diaphragm 26, the operation of lever 20 to control the throttle 14. Lever 20 is guided in a loop 44 which is fixed to frame-bar 21 and an adjustable-screw 45 is secured in the outer end of said loop to limit the outward movement of the inner end of the lever. A valve 47 is included in pipe 36 between the water-diaphragm and the water jacket, so that the water-operated regulator may be rendered inoperative if desired.

In operation, the pressure against diaphragm 34 is variable and in accordance with the speed of the motor, since this varying pressure is generated through the circulating pump which is driven by the motor. The operator will control the throttle through valve 29 by which compressed air will be delivered against one side of the diaphragm 26 which will cause it to operate stem 25 and lever 20 against the force of spring 30 and also against the force of the water pressure against diaphragm 34. The operation of the lever 20 by the compressed air will shift rod 23 to correspondingly open the throttle 14 which controls the supply of combustible fluid to the motor cylinders. Assuming air of a given pressure to have been admitted to the casing of diaphragm 26, to operate the throttle for a given speed of the motor, any fluctuations in the speed of the motor will cause corresponding variation in the pressure of water against the diaphragm 34 to automatically regulate the position of lever 20 so as to operate the lever 20 to partially close the throttle in degree corresponding to the pressure variation of the water in the water-jacket. The pressure of air against the diaphragm 26, which is variable at the will of the operator through valve 29, regulates the speed of the motor generally. The variation of the water pressure against diaphragm 34 exerts

the ground pressure to lever 20 which is variable according to the variation in the speed of the motor and consequently the controlling mechanism is adapted to provide a very minute adjustment by which the desired speed may be maintained and which is of advantage in instances where it is desired to synchronize the operation of a plurality of motors.

The invention exemplifies improved controlling mechanism for an internal combustion motor which is adapted to be controlled from a remote point and in which the varying pressure of the cooling liquid in the water-jacket is used in regulating the speed of the motor under control of the air-operated diaphragm which is controllable at the will of the operator. The purpose of providing an adjustable spring pressure for the lever 20 is to permit a plurality of motors to be identically adjusted to operate at the same speeds, notwithstanding a variable action in the governor, due to friction or otherwise.

The invention is not to be understood as restricted to details set forth, since these may be modified within the scope of the appended claims, without departing from the spirit and scope of the invention.

Having thus described the invention, what I claim as new and desire to secure by Letters Patent, is:

1. The combination with a water-jacketed motor, of a throttle for controlling the supply of fuel thereto, and means for controlling the throttle comprising a lever connected to said throttle, a fluid regulator connected to said lever and responsive to fluctuations of pressure in the water-jacket, a device operable by compressed air and connected to shift the lever to open said throttle, and an adjustable spring tension device connected to and adapted to retract said lever.

2. The combination with a water-jacketed motor, of a throttle for controlling the supply of fuel thereto, and means for controlling the throttle comprising a lever connected to said throttle, a fluid regulator connected to said lever and responsive to fluctuations of pressure in the water-jacket, a diaphragm operable by compressed air and connected to shift the lever to open said throttle, and adjustable spring means connected to and adapted to retract said lever.

Signed at Green Bay, Wis., this 5th day of September, 1923.

LEE W. MELCHER.
